CLAIM

The ornamental design for a traction control device, as shown and described.

DESCRIPTION

FIG. 1 is a top rear perspective view of a traction control device showing my new design.

FIG. 2 is a top front perspective view thereof.

FIG. 3 is a bottom rear perspective view thereof.

FIG. 4 is a bottom front perspective view thereof.

FIG. 5 is a top plan view thereof.

FIG. 6 is a bottom plan view thereof.

FIG. 7 is a rear elevational view thereof.

FIG. 8 is a front elevational view thereof.

FIG. 9 is a left side elevational view thereof; and,

FIG. 10 is a right side elevational view thereof.
